UNITED STATES PATENT OFFICE

LEWIS R. SAMMETH, OF GOLDSBORO, NORTH CAROLINA

TOBACCO CLEANING MACHINE

Application filed October 16, 1930. Serial No. 489,150.

In preparing tobacco leaves for the manufacture of cigars, cigarettes and chewing tobacco, the hands of leaves after curing, are carried by an endless conveyor through a so-called re-dryer, effecting drying of the leaves to a predetermined extent so that when they are moistened to prevent crumbling during manufacture, it may be insured that such moistening will be uniform. It is now customary to take the leaves as they come from storage and curing houses, hogsheads or the like, and direct them through the re-dryer, but much better products can be obtained if all dust be removed from the tobacco hands before passing them through the re-drying machine. It is hence one object of my invention to provide a novel machine for removing all dust from the hands of tobacco before they enter the re-dryer. A further object is to provide said machine with means for first separating and upwardly moving the leaves of the suspended hands so as to blow out dust which could not otherwise be reached, and to provide additional means for then blowing the leaves again downwardly, not only restoring them to orderly positions for passage through the re-dryer, but blowing off all remaining dust.

A still further object is to provide a machine of the class above mentioned, which may be rather easily and inexpensively manufactured and marketed, yet one which will be highly efficient and durable.

With the foregoing in view, the invention resides in the novel subject matter herein-after described and claimed, description being accomplished by reference to the accompanying drawings.

Fig. 1 is a side elevation partly in section.

Fig. 2 is an end elevation partly in section, the conveyor-guiding sprockets and their shafts being omitted.

Fig. 3 is a plan view of one of the gangs of suction heads which remove the dust from the vicinity of the path along which the hands of tobacco are conducted by the conveying means.

Fig. 4 is an edge elevation of the gang of suction heads shown in Fig. 3.

Fig. 5 is a side elevation of one of the air-directing nozzles.

Fig. 6 is a vertical longitudinal section through the nozzle shown in Fig. 5.

Fig. 7 is a plan view of the same nozzle. 55
Figs. 8 and 9 are vertical transverse sectional views on lines 8—8 and 9—9 respectively of Fig. 6.

The machine is shown at the inlet end of a conventional re-dryer 10, and two sets of track-supported conveying chains 11, forming parts of said re-dryer, also form parts of said machine, these chains being trained around shaft-carried sprockets 12, suitably located. The chains 11 embody the usual hooks 13 for supporting the transverse rods 14 upon which the hands of tobacco 15 are suspended, the rods with the hands of tobacco being placed upon the chains at the inlet end E of the machine, being carried through the present "dusting" machine and the re-dryer 10, by said chains, and removed by hand at the delivery end of said re-dryer. 60

The machine herein disclosed embodies two units U and U', both being mounted upon a suitable frame F. With certain exceptions hereinafter described, these units are identical and hence a description of the unit U will suffice for both. This unit embodies a transverse horizontally elongated 80 nozzle 16, disposed under the path along which the tobacco hands 15 are conveyed, said nozzle 16 being near the receiving end E of the machine. This nozzle 16 is adapted to direct an upward blast of air for the purpose of separating the leaves of the tobacco hands 15 as indicated toward the right of Fig. 1, thereby effectively blowing out all dust in the leafy portions of said hands. 85 Above the path along which the hands of tobacco are conveyed, and disposed over the nozzle 16, is a gang of suction heads 17 which are instrumental in carrying off the dust blown from the tobacco leaves.

Spaced toward the delivery end of the 95 machine, from the nozzle 16, and disposed above the path along which the tobacco hands are conveyed, is another transverse horizontally elongated nozzle 18. After the tobacco leaves have been blown upwardly 100

by the blast of air from the nozzle 16, the blast of air from the nozzle 18 again blows said leaves downwardly into orderly fashion, as illustrated in Fig. 1, said blast from the nozzle 18 blowing off all remaining dust. Under this nozzle 18 and below the path along which the tobacco hands are carried, is a second gang of suction heads 19 which are instrumental in carrying off the dust blown downwardly by the blast of air from said nozzle 18.

Air-conducting pipes 20 and 21 lead to the nozzles 16 and 18 respectively, these pipes of the unit U being supplied with air under pressure by means of a blower 22, while the corresponding pipes of the unit U' are fed from another blower 22'. Both of these blowers are driven by pulleys and belting 23 or other desired means, from a main drive shaft 24, the latter being in turn driven by an electric motor 25, through the instrumentality of a belt and pulleys 26, or other desired driving connection.

A horizontal suction pipe 27 is connected by branch pipes 28 with the suction heads 17 of the two units U and U', and another suction pipe 29 is connected by branches 30 with the suction heads 19 of said units U and U'. The suction pipes 27 and 28 communicate with a suction manifold 31 which in turn communicates with an exhaust fan 32, this fan being driven from the shaft 24, by a belt 33 and pulleys, or by other appropriate means.

It will be seen from the above that as the hands of tobacco advance in the direction of the arrow A of Fig. 1, the blast of air from the nozzle 16 will upwardly blow the tobacco leaves and effectively blow out all dust within the hands, this dust being carried off through the suction heads 17, piping 28-27-31 and the exhaust fan 32. As the hands of tobacco reach a position under the nozzle 18, the air blast from this nozzle again blows the tobacco leaves downwardly into orderly fashion, and at the same time all remaining dust is blown from said leaves, this dust being carried off by the suction heads 19, the piping 30-29-31 and the exhaust fan 32. Thus, the leaves will pass on to the re-dryer in a thoroughly dusted condition and even though the leaves are again blown downwardly by the blast from the nozzle 19, they will not be in such compact relation as when initially fed into the machine. On the contrary they are in more or less loose condition with regard to each other, so that the re-dryer may more effectively perform its work.

The constructions of the suction heads and the air nozzles may of course vary in numerous ways, but the structures shown are efficient and may be followed if desired. All of the gangs of suction heads may be identical and in Figs. 3 and 4, I have detailed

the heads 17. All of these heads are secured together in side by side relation and at the ends of the gang, outwardly declined plates 34 are provided, said plates and gang co-operating in forming a hood-like structure 70 under which the leaves are conveyed, so that the suction created by the heads 17 will be localized where needed. The lower edges of the plates 34 are preferably provided with outstanding flanges 35 which may be secured upon longitudinal bars 36 forming parts of the frame F.

All of the nozzles 16 and 18 are preferably of the same construction, and in Figs. 5 to 9, I have detailed one of said nozzles 16. 80 While this nozzle is horizontally elongated, its bottom is preferably inclined somewhat as shown in Figs. 5 and 6, and the dimension of said nozzle measured transversely of its length in a horizontal direction, preferably decreases gradually away from the pipe 20. The general shape of the nozzle may be polygonal in transverse section but it preferably embodies two longitudinal upwardly converging walls 37, between the upper edges of which, the air outlet throat 38 exists. At the end of this throat toward the pipe 20, there is preferably an end wall 39 declining toward said pipe 20 and connecting the side walls 37.

The novel construction above described insures uniform discharge of air throughout its length so that the best results are obtainable.

The suction heads 19 may be considered 100 simply as the suction heads 17 inverted. Similarly, nozzle 18 is virtually nozzle 16 inverted.

It will be seen from the foregoing that a novel and advantageous machine has been 105 provided, and while the details shown may be considered as preferred, it is to be understood that within the scope of the invention as claimed, numerous variations may be made. Moreover, in the treatment of tobacco hands, the method step of directing a blast of air endwise into the leafy ends of the hands for the purpose explained, may well be carried out in ways other than the specific manner herein described. This is also true 115 with regard to the additional step of directing an air blast endwise against the butt ends of the hands after subjecting the latter to the first blast.

I claim:

1. In a cleaning machine for hands of tobacco, a conveyor for the tobacco hands, and means for directing an air blast endwise into the leafy ends of said tobacco hands while the latter are being conveyed 125 by said conveyor.

2. In a cleaning machine for hands of tobacco, a conveyor for the tobacco hands, means for directing an air blast endwise into the leafy ends of said 130

hands while the latter are being conveyed by said conveyor, and means for directing a blast of air endwise against the butt ends of the hands after the latter have left the 5 first named means.

3. In a cleaning machine for hands of tobacco, a conveyor having means for suspending the tobacco hands with their butts presented upwardly, means under the path 10 along which the hands are conveyed for directing an upward blast of air to separate and raise the tobacco leaves and blow dust therefrom, an additional means over said path for directing a downward blast of air to again lower the leaves and blow remaining dust therefrom.

4. A structure as specified in claim 3; together with suction means over said first 20 named air directing means and path, and additional suction means under said additional air directing means, said suction means being adapted to conduct the removed dust from the vicinity of the aforesaid path.

5. In a cleaning machine for hands of tobacco, a conveyor having means for suspending the tobacco hands with their butts presented upwardly, a transverse horizontally elongated air discharge nozzle under the path along which the tobacco hands are 25 conveyed, said nozzle being adapted to discharge an upward blast of air to separate and raise the tobacco leaves and blow dust therefrom, a second transverse horizontally elongated air discharge nozzle above said 30 path and disposed between the first named nozzle and the delivery end of the machine, said second nozzle being adapted to discharge a downward blast of air to again lower the tobacco leaves and blow remaining dust therefrom, and air blast conducting 35 passages leading to said nozzles.

6. A structure as specified in claim 5; together with a transverse gang of suction heads over the first named nozzle and said path, an additional transverse gang of suction heads under said path and said second nozzle, and suction passages leading from 40 said suction heads to conduct the removed dust to a remote point.

50 7. In a method of treating tobacco hands, the step of directing a blast of air endwise into the leafy ends of the hands to separate the leaves and blow out dust.

8. In a method of treating tobacco hands, 55 the step of directing a blast of air endwise into the leafy ends of the hands to separate the leaves and blow out dust, and the additional step of directing an air blast endwise against the butt ends of the hands after subjecting the latter to the first blast, thereby 60 restoring the leaves to orderly fashion and blowing off remaining dust.

In testimony whereof I affix my signature.
